ATTORNEY

UNITED STATES PATENT OFFICE

EDWARD J. SITHENS, OF CYNWYD, PENNSYLVANIA

BOOKHOLDER

Application filed August 4, 1930. Serial No. 472,941.

This invention relates to book holders, an object being to provide a desk drawer, cabinet or other casing for housing a series of books or binders to contain the books, such as telephone directories or the like, so that they occupy a relatively small space and are supported in such manner as to be conveniently accessible for use.

Another object of the invention is to provide a pivotal mounting for the books so that they may be pulled out of the casing into position for use and pushed back into the casing after being used.

The novel features which are considered characteristic of this invention are set forth with particularity in the appended claims. The invention itself, both as to its organization and method of operation, together with other objects and advantages thereof, will be further explained in the following description having reference to the accompanying drawings consisting of the following figures:

Figure 1 illustrates the improved device as applied to the drawer of a desk;

Fig. 1A is a side view of the device detached and having a book mounted thereon;

Fig. 2 is an end view of Fig. 1, showing a book supported on the bracket in an open or reading position;

Fig. 3 is a view of the device showing it applied to a wall booth;

Fig. 4 is a front view of Fig. 3 showing a series of books in normal position in the booth;

Fig. 5 is an end view of a cabinet showing a book associated therewith in normal position in dotted lines and in an extended or reading position in full lines; and

Fig. 6 is a front view of Fig. 5 showing a series of books in normal position in the cabinet.

Referring to the drawings in which the improved device is illustrated, the character 5 designates a bracket which includes two terminal arms 6 and 7 which are interconnected by an intermediate arm 8. Each of these elements is preferably flat. The arm 7 is suitably affixed in pivoted relation to one 50 end of a supporting plate 9 at a point to pro-

vide a proper balance for the supporting plate. The other end of the supporting plate extends beyond the arm 7 and the length of the supporting plate corresponds to the length of the book which it is to carry. The 55 arm 8 is hingedly connected at one end to the arm 6 by means of a joint 10 and at the other end to the arm 7 by means of a joint 11. When the arm 6 of the bracket is attached to a casing, as will later appear, the joint 10 will form a fixed axis about which the remainder of the bracket and the supporting plate may rotate, and the joint 11 will form a movable axis about which the arm 7 and the supporting plate 9 may rotate. 60

The lower surface of the plate 9 may be provided with a longitudinal depression in one end of which the arm 7 is seated. The other portion of the depression may be provided with a filler 12 of such material as 65 cardboard or the like, of a thickness substantially equal to that of the arm 7. A reinforcing strip 13 is riveted or otherwise suitably secured to one face of the arm 8 and extends slightly beyond the joint 11. The end 70 14 of this strip engages the back of the plate 9 when it is in extended position, as more clearly indicated in Fig. 1A, and provides a stop and support for said plate. The elements of the bracket and supporting plate may be provided with a covering 15, for instance leather 75 veneer. A spring clip 16 is secured to an end of the supporting plate 9 and a cooperating spring clip 17 is secured to the arm 8. These clips frictionally engage with each 80 other when the bracket is in collapsed and semi-extended positions to clamp the arms 7 and 8 together. The resilient clips 16 and 17 keep the arms 7 and 8 locked together while the book is being withdrawn or returned to 85 its housing. Said clips prevent the arms from springing apart and causing an awkward movement of the arms and a possible jamming of the book in the housing. The action of the clips also insures a smooth and 90 regular line of motion of the book upon being returned to its housing and prevents any irregular movement of the arms. The supporting plate 9 has a book 18 secured to its flat top side. In the present instance, this 95 100

book is shown as being mounted within a binder having stiff covers or side supports 22 which are pivoted to the edges of the supporting plate 9 by piano hinges or the like which lie along axes in planes perpendicular to the plane of the axis of the pivot 11 on which the supporting plate rotates.

The bracket is adapted to be mounted in various articles of furniture, and in Figs. 1 10 and 2 it is shown as applied to the drawer of a desk. The terminal arm 6 is fastened by screws passing through openings in said arm to an inner reinforced side wall 19 of the drawer. It will be obvious that the device 15 may be applied to a drawer positioned on the right or left side of a desk. The outer wall of the desk drawer may be cut away to provide clearance for the book when it is rotated from or returned to the drawer. A series of 20 books, such as telephone directories for different sections, may be mounted in the drawer, as shown in Fig. 2. A stop strip 20 is secured to the side wall 19 against which the edges of the books rest when in position in the 25 drawer. In Fig. 1 the book is shown in its various positions. In "position 1", the book is shown in its normal position within the drawer, and the arms 7 and 8 and supporting plate 9 are collapsed. In "position 2" the 30 book is rotated to a semi-extended position, and in "position 3" the book is again rotated and assumes a fully extended position ready to be opened to a reading position, such as shown in Fig. 2. The side wall 19 is beveled 35 at an upper corner to permit the inclination of the arm 8, as shown in Fig. 1A. Arm 8 is held in this inclined position by reinforcing strip 13 resting against the shoulder stop 29 at pivot 10, thereby providing a support 40 for said arm at this point. In the open or reading position of the book the arms 7 and 8, with the supporting plate 9, assume a substantially T-shaped formation. In this 45 position the stop 14 engages the back of the plate 9 and the shoulder stop 29 engages the end of strip 13, thereby jointly providing a support for plate 9 and arm 8 when the book is in an open or reading position. The supporting plate 9 is provided with longitudinal 50 edges 21 which extend slightly outward therefrom and serve as supports for the covers 22 of the book. The book in its open or reading position lies in a plane at right angles to the plane in which the arms 7 and 8 rotate.

In Figs. 3 and 4 the bracket is applied to a booth 23 which is mounted on a supporting wall 24. The booth may be provided with an inclined supporting base 25 for the bracket and books, and a stop plate 26 serves as a 55 rest for the books when in normal position. The top edges of the end walls 27 may be also inclined, as shown. The book will lie in its normal position as indicated by dotted lines in Fig. 3 and in its extended position as indicated by full lines in this figure.

In Figs. 5 and 6 the brackets are shown as being positioned in a compartment provided in a cabinet 28. The mounting and operation of the brackets in the cabinet will be similar to that outlined in connection with their mounting and operation in the desk drawer, as described above.

The book, or binder which encloses the book is raised from its normal or housed position in the desk drawer, booth, or cabinet by grasping the back or far edge of the binder, and pulling it up and forward in an arc until the movement is arrested by the shoulder stop 29 which then holds the arm 8 in the inclined position—the spring clips 16 and 17 remaining interlocked during this operation. A slight downward pressure is then exerted on the book which releases and unlocks the spring clips 16 and 17, and the book is again rotated through a second arc until the movement is again arrested by the stop 14 carried by the intermediate arm which then supports the binder. At this time the book may be opened to a reading position. The book is held in this position by the force of gravity exerted against the supporting stops 14 and 29. The covers of the book or binder when opened rest upon the longitudinal edges 21 on the supporting plate, so that the pages of the book are in a convenient position for reading.

The restoration of the book and binder to their normal position is effected by closing the covers and rotating the book and binder upward and backward to the point where the clips engage the two movable arms and clasp them together. The book is again rotated through an arc and restored to the casing.

What is claimed is:

1. In a book holder, the combination of a housing for books and a bracket for supporting the books, said bracket including an inner arm fixed to said housing and an intermediate and outer arm hingedly connected together and being rotatable with respect to each other and with respect to said inner arm, the intermediate arm having a book pivotally connected therewith, and a stop formed on said housing to limit the outward swing of the intermediate arm.

2. In a book holder, the combination of a housing for books and a bracket for supporting the books, said bracket including an inner arm fixed to said housing and an intermediate and outer arm hingedly connected to each other and being rotatable with respect to each other and with respect to said inner arm, the intermediate arm having a book pivotally connected therewith and adapted to be rotated thereon to a reading or open position lying in a plane at right angles to the plane in which said arms rotate, and a stop formed on said housing to limit the outward swing of the intermediate arm.

3. In a book holder, the combination of a housing for books and a bracket for supporting the books, said bracket including an inner arm fixed to said housing and an intermediate and outer arm hingedly connected to each other and being rotatable with respect to each other and with respect to said inner arm, the intermediate arm of said pair having a book pivotally connected therewith and adapted to be rotated thereon to a reading or open position lying in a plane at right angles to the plane in which said arms rotate, a stop member associated with one of said arms for arresting the movement and supporting said book, and means formed on said housing to limit the outward swing of the intermediate arm. 10
4. In a book holder, the combination of a housing for books and a bracket for supporting a book, said bracket including two terminal arms and an intermediate arm hingedly connected at its ends to the terminal arms, one of the terminal arms being fixed to said housing and the other of said terminal arms 20 having a book attached thereto, and a stop formed on said housing to limit the outward swing of the intermediate arm. 25
5. In a book holder, the combination of a housing for books and a bracket for supporting a book, said bracket including two terminal arms and a hingedly connected intermediate arm and being adapted with the book to assume a position in collapsed relation within the housing and a position in 30 extended relation from the housing, one of said terminal arms being affixed to said housing in the collapsed and extended positions of the bracket and the other terminal arm and intermediate arm being at right angles 35 to the fixed arm in their collapsed position and being rotatable about an axis to assume a substantially inverted L-shaped formation in extended position. 40
6. In a book holder, the combination of a housing for books and a bracket for supporting a book, said bracket including an arm, said arm having one end pivoted to said housing, a back support for a book pivoted to the opposite end of said arm, and side 45 supports for the book pivoted to said back support along axes in planes perpendicular to the plane of the axis of the pivot of said back support, and a stop formed on said housing to limit the outward swing of the 50 pivoted arm. 55
7. In a book holder, the combination of a housing for books and a bracket for supporting the books, said bracket including an arm affixed to said housing and a pair of 60 arms hingedly connected together and being rotatable with respect to each other and with respect to said fixed arm, the outer arm of said pair having a book attached thereto, said arm with the book being adapt- 65 to assume a collapsed position within the 100
- housing, a semi-extended position and a full extended position from said housing, and resilient means associated with each of the hingedly connected arms and cooperating with each other to interlock the latter arms during the collapsed and semi-extended positions of the bracket. 110
8. In a book holder, the combination of a housing for books and a bracket for supporting a book, said bracket including two terminal arms and an intermediate arm hingedly connected at its ends to the terminal arms, one of said terminal arms being fixed to said housing and the other of said terminal arms having a book attached thereto, said arm with said book being adapted to assume a collapsed position within the housing, a semi-extended position and a full extended position from said housing, and resilient means carried by one of the terminal arms and by said intermediate arm cooperating with each other to interlock said terminal and said intermediate arm in the collapsed and semi-extended positions of said bracket. 120
- In testimony whereof, I have signed my name to this specification this twenty-ninth day of July, 1930. 125
- EDWARD J. SITHENS. 130
